UNITED STATES PATENT OFFICE.

ERNEST F. SCHURMAN, OF NEW YORK, N. Y.

UNIVERSAL JOINT.

1,191,739.

Specification of Letters Patent. Patented July 18, 1916.

Application filed July 9, 1914. Serial No. 849,929.

To all whom it may concern:

Be it known that I, ERNEST F. SCHURMAN, a citizen of the United States, and a resident of the city of New York, borough of the Bronx, in the county of the Bronx, State of New York, have invented a new and Improved Universal Joint, of which the following is a full, clear, and exact description.

10 My invention has for its object to provide a universal joint having its two parts connected by a ball and socket joint, one of the parts having a cylindrical portion with a plurality of slots spaced apart and disposed longitudinally of the axis of the part, pins which extend from the other part, being movably disposed in the slots. The sides of each of the slots diverge for a distance from its center in the direction of its ends so that 20 the pins which fit the slots at their centers, may move laterally for a distance relatively to the part having the slots, as the pins move in the slots toward their ends. With this construction the parts, when they are in 25 alinement, will act as a flexible coupling, while the pins and the width of their corresponding slots between their centers and their ends, will arrange for the rotation of one of the parts by the other, when the axes 30 of the parts are disposed at any desired angle.

Additional objects of the invention will appear in the following specification in which the preferred form of my invention 35 is disclosed.

In the drawings similar reference characters refer to similar parts in all the views in which—

Figure 1 is a sectional view showing the 40 invention; Fig. 2 is a plan view with parts broken away to show the construction of the slots; Fig. 3 is a sectional view on the line 3—3 of Fig. 1; and Figs. 4 and 5 are views showing the modified form of the invention, 45 Fig. 4 being a sectional view, and Fig. 5 being an end view of Fig. 4.

By referring to the drawings it will be seen that a cylindrical member 10 is provided having a head 11 with an opening 12

in which a rod 13 may be disposed, the rod 50 13 being held in position in the opening 12 by a set screw 14. A cylinder 15 of the cylindrical member 10 has slots 16 which are spaced apart and which are disposed parallel with the axis of the cylinder. As 55 will be best seen by referring to Fig. 2 of the drawings, the sides of the slots 16 diverge for a distance from their centers 17 in the direction of their ends 18, so that the pins 19 which are movably disposed in the 60 said slots 16, will be prevented from lateral movement relatively to the cylinder 15, when the said pins 19 are at the centers 17 of the slots 16, the pins 19 being permitted to move laterally for a distance relatively to the 65 cylinder 15 when the pins 19 move in the direction of the ends 18 of the slots. These pins 19 are mounted on a concavo-convex member 20 which extends from the base 21. Extending also from this base 21 there is a 70 shank 22 with a ball-bearing member 23 journaled in a concave bearing 24 which extends from the head 11. This concave bearing 24 has a companion bearing member 25 which may be constructed in sections and 75 which is disposed around the ball-bearing 23, and which is held against the concave bearing 24 by means of the screws 26, the screws 26 being disposed in the orifices 27 in the companion bearing member 25, and 80 meshing in the threaded orifices 28 in the concave bearing 24. These screws 26 may be inserted through the openings 29 in the concavo-convex member 20, this concavo-convex member 20 being disposed around 85 the concave bearings 24 and 25, and being disposed within the cylinder 15, as has been stated. The pins 19 may be threaded at 30 for meshing in the threaded orifices 31 in the concavo-convex member 20, and these 90 pins 19 may also have additional threads 32 meshing in threaded orifices 33 in a ring 34 which is disposed around the cylinder 15. The pins 19 may be prevented from turning in one direction by means of the cotter pins 95 34 which engage the inner sides of the ring 34, and the pins 19 may be prevented from turning in the other direction by the shoul-

ders 35 which engage the outer sides of the concavo-convex member 20. In the base 21 there is an opening 36 in which is disposed a rod 37, the rod 37 being held in position by 5 a set screw 38.

The rod 37 with the base 21, may be moved to the position shown by the dotted lines shown in Fig. 1, and when in this position, the rod 37 will be rotated by the rotation 10 of the rod 13, for the cylinder 15 at the sides of the slots 16 will engage one or more of the pins 19 to rotate the concavo-convex members 20 with its base 21, the pins 19 moving back and forth in the slots 16 and having 15 sufficient lateral play relatively to the cylinder 15 to prevent binding when one of the slots 16 moves away from the base 21, and until the next slot 16 moves into the position previously occupied by the slot 20 which is moved away from the said base.

In the modified form of the invention shown in Figs. 4 and 5 of the drawings, rollers 39 are mounted on the pins 19, and the ring 34 is connected with the base 21 by 25 means of arms 40, these arms being held in position by set screws 41 which are disposed in orifices 42 in the arms 40, and which mesh in threaded orifices 43 in the base 21. However, if desired, the arms 40 may be 30 made integral with the base. In other respects the modified form of the invention shown in Figs. 4 and 5 corresponds with the invention as shown in Figs. 1, 2 and 3 of the drawings.

35 It will be understood that the pins and the slots may be arranged so that the joint will operate with the rods 13 and 37 disposed at any desired angle less than ninety degrees. When there is no thrust on the rods or shafts 40 13 and 37, the ball and socket joint may be omitted. When the rods or shafts 13 or 37 are disposed in alinement, all the pins will be in the narrow portions of the slots and the device will act as a flexible coupling.

45 Having thus described my invention I claim as new and desire to secure by Letters Patent:

1. In a universal joint, a hollow member having longitudinally extending slots, the 50 sides of each of the slots diverging for a distance from its center in the direction of its ends, a member disposed in the hollow member, pins on the second member and disposed in the slots, a ring disposed around the hollow member to which the pins are secured, and means to prevent the longitudinal movement of the members relatively to each other.

2. In a universal joint, a hollow member 60 having longitudinally disposed slots, the sides of each of the slots diverging for a distance from its center in the direction of its ends, a member disposed in the hollow member, pins on the second mentioned member

and disposed in the slots, a ball and socket joint connecting the two members and disposed within the hollow member, and a ring around the hollow member to which the pins are secured.

3. In a universal joint, a hollow member 70 having longitudinally disposed slots spaced apart, a member having an extended base and disposed in the hollow member, pins on the last mentioned member and disposed in the slots, a ring disposed around the hollow member, to which the pins are secured, and arms connecting the ring with the base of the second mentioned member, for holding the ring rigid relatively to the second mentioned member. 80

4. In a universal joint, a hollow member having longitudinally disposed slots and a head, the hollow member being provided with a concave bearing at the head, there being a threaded orifice in the concave bearing, 85 a ball disposed on the concave bearing, a concavo-convex member secured to the ball and disposed between the slots in the hollow member and the concave bearing, pins on the concavo-convex member disposed in the slots, a companion bearing member having an orifice, disposed around the ball and against the first concave bearing, and a screw disposed in the orifice and meshing in the threaded orifice, there 90 being an orifice on the concavo-convex member through which the screw may be inserted. 95

5. In a universal joint, a hollow member having longitudinally disposed slots and a head, the sides of each of the slots diverging from the center in the direction of its ends, the hollow member having a concave bearing extending from its head and provided with a threaded orifice, a ball disposed in 100 the concave bearing, a concavo-convex member secured to the ball and disposed between the slots on the hollow member and the concave bearing, pins on the concavo-convex member disposed in the slots, a companion bearing member having an orifice and disposed around the ball and against the first 105 mentioned concave bearing, and a screw disposed in the orifice and meshing in the threaded orifice, there being an orifice in the 110 concavo-convex member through which the screw may be inserted. 115

6. In a universal joint, a hollow member having longitudinally disposed slots and a head, the hollow member having a concave 120 bearing extending from the head and provided with a threaded orifice, a ball disposed in the concave bearing, a concavo-convex member secured to the ball and disposed between the slots in the hollow member and 125 the concave bearing, pins on the concavo-convex member disposed in the slots, a companion bearing member having an orifice

and disposed around the ball and against the concave bearing, a screw disposed in the orifice and meshing in the threaded orifice, there being an orifice in the concavo-convex member through which the screw may be inserted, and a ring disposed around the cylindrical member, to which the pins are secured.

In testimony whereof I have signed my name to this specification in the presence of two subscribing witnesses.

ERNEST F. SCHURMAN.
